UNITED STATES PATENT OFFICE.

GRADY E. FAIRCLOTH AND WILLIAM M. MOSELEY, OF PORT ARTHUR, TEXAS, AS
SIGNORS TO THE TEXAS COMPANY, OF NEW YORK, N. Y., A CORPORATION OF
TEXAS.

PORTABLE ATTACHMENT FOR CONVEYERS.

Application filed November 28, 1919. Serial No. 341,145.

To all whom it may concern:

Be it known that we, GRADY E. FAIRCLOTH and WILLIAM M. MOSELEY, both citizens of the United States, and both residents of 5 Port Arthur, county of Jefferson, and State of Texas, have invented certain new and useful Improvements in Portable Attachments for Conveyers, of which the following is a specification.

10 Our invention relates to conveyers and other apparatus for manipulating cases and packages and has special reference to means for taking cases or packages from storage tiers and delivering them to a continuously 15 operating conveyer.

One object of our invention is to provide a relatively simple and effective conveyer attachment that shall be readily portable from one location to another and particularly 20 adapted for carrying boxes or cases from the top of tall stacks in a storage warehouse, and delivering them at regular predetermined intervals to a continuously operating conveyer.

25 In order that our invention may be thoroughly understood, we will now proceed to describe the same in the following specification, and will then point out the novel features thereof in appended claims.

30 Referring to the drawings:

Figure 1 is a side elevation of a conveyer attachment arranged and constructed in accordance with our invention and constituting an embodiment thereof.

35 Figure 2 is a plan view of the same apparatus.

Figure 3 is a partially sectional elevation corresponding to Figure 1.

40 Figure 4 is a partially sectional plan view corresponding to Figure 2.

Figure 5 is a partially sectional elevation illustrating the portability of the apparatus.

45 The structure illustrated comprises a frame 10 which is supported for transportation on wheels 11 and 12 but may be supported on the wheels 11 and on jack screws 13 when the device is operating in a fixed position.

50 The frame 10 is triangular in side eleva-

tion and supports an inclined, laterally movable chute 14. In addition the frame supports a pair of oppositely extending 90 degree roller gravity chutes 15 and 16 which are arranged to deliver packages and boxes to the 55 top of the chute 14, the latter being adjusted in position to cooperate with either the one or the other of the gravity chutes. In Figure 2 the laterally adjustable chute 14 is shown cooperating with the 90 degree roller 60 gravity chute 15.

The adjustment of the chute 14 is effected by means of a pair of spaced adjusting screws 17 and 18 which are interconnected by sprocket wheels 19 and chain 20 or by 65 other suitable gearing so that they operate concurrently when the crank or other suitable lever 21 is attached to either of them and operated.

The chute 14 comprises a frame structure 70 22 on which are supported a plurality of shafts 23, 24, 25, 26 and 27. A sprocket wheel 28 is secured to the shaft 23, and cooperates with the driving sprocket 29 in supporting an endless chain or belt 30, to which 75 lugs 31 are secured. A gear wheel 32 is also secured to shaft 24 and meshes with the gear wheel 33 on shaft 25. The chute 14 further comprises a conveyer belt or chain 34, having a plurality of spaced lugs 35 thereon, 80 which extends over and is driven by a sprocket wheel 36 on shaft 25. The belt or chain 34 also cooperates with idler sprockets 37 on shaft 26, and 38 on shaft 27. The shaft 27 is adjustable in response to takeup 85 screws 39 and the shaft 23 is adjustable in response to takeup screws 40, thus the chains or belts 30 and 34 are maintained taut.

Mounted on the shaft 26 is a brake drum 41 with which cooperates a brake band 42, 90 the arrangement being such as to preclude too great a freedom of movement of the chain 34. When the apparatus is supported by the wheels 11 and 12 as shown in Figure 5, wheel frames 43 are fastened in a 95 fixed position to the frame 10 by means of pins 44 and the machine may be guided and drawn about by workmen by means of handles 45 pivotally attached to wheel forks 46. The wheels 11 are mounted in the forks 100

46 which are supported in bearing brackets 47 on the frame and are free to turn to constitute steering wheels.

The operation of the apparatus is as follows:

Assuming that the machine is wheeled to a position over a travelling apron conveyer 48 having upwardly extending lugs or flights 49, which position is adjacent to the tiers 10 or stacks of boxes or cases which are to be transferred to the conveyer. When the apparatus is so located, the jack screws 13 are screwed downwardly by means of cranks 50 so as to take the weight of the frame from 15 the wheels 12 and permit the pins 44 to be removed. The frame is then lowered by turning the screws in the reverse direction until the projections 31 of the chain 30 come into the range of and are driven by the 20 flights or lugs 49 of the apron conveyer.

Assuming that the apron conveyer is moving in the direction of the arrow 51, the result is that the chain 30 is actuated and drives the sprocket 29. This in turn drives 25 the gears 32 and 33, the sprocket 36 and causes the chain or link belt 34 to travel in the direction of the arrow 52.

Cases or boxes which are to be lowered to the main conveyer 48 are fed into the 30 machine at the upper end of gravity chute 15 from which they enter the top of the auxiliary conveyer or chute 14. The cases or boxes engage the successive lugs 35 and slide down the chute 14 by gravity, their 35 speed, however, being determined by the lugs 35 which travel at a substantially uniform rate determined by the movement of the main conveyer.

The boxes or cases are released as each lug 40 swings downwardly at the sprocket wheel 36. At this point the case or box, such as the case 53 of Figure 3, slides out of the chute at the lower end and is delivered to the apron conveyer 48. The arrangement of 45 lugs 35 is such that each case is dropped on to the main conveyer between the lugs or flights 49 thereof, and is straightened on the conveyer by flexible arms or fingers 54 which are attached to the bottom of the 50 chute.

If it is more convenient to feed the boxes or cases into the roller gravity chute 16 the chute 14 is adjusted laterally from the position shown in Figure 2, to a corresponding 55 position on the opposite side where it is in position to cooperate with the chute 16. The lateral adjustment being accomplished as hereinbefore set forth by means of screws 17 and 18.

An apparatus of preferred form and construction has been illustrated and described for the purpose of showing a way in which this invention may be used, but the inventive thought upon which this application is

based, is broader than the illustrative embodiment thereof, and we therefore intend no limitations other than those imposed by the appended claims.

What we claim is:

1. In combination with a traveling main 70 conveyer having a plurality of upwardly extending lugs, an auxiliary conveyer that comprises an endless belt arranged in co-operative relation to said main conveyer for the exchange of packages therewith and 75 means for driving said endless belt adapted to be actuated by said lugs on the main conveyer.

2. A portable attachment for traveling belt conveyers having a series of flights, that 80 comprises an endless belt arranged in co-operative relation to the conveyer for the exchange of packages therewith, and a driving mechanism for the endless belt of the attachment adapted to be actuated by the 85 flights of the traveling belt conveyer.

3. An attachment for conveyers having a movable member with flights thereon, comprising a portable means for feeding objects from a higher level to the conveyer, 90 and means adapted to be actuated by said flights for operating the feeding means of the attachment.

4. A portable attachment for conveyers having a movable member with flights arranged at intervals thereon, comprising a frame, feeding means mounted thereon and arranged to transmit objects from a higher level to the conveyer, a belt for operating 100 said feeding means and a driving mechanism for the attachment adapted to be actuated by the flights on the main conveyer.

5. A portable attachment for a main conveyer having a continuously movable member, comprising a frame, a pair of chutes 105 extending in different directions, an endless belt for guiding packages on to said main conveyer adapted to be adjusted to cooperate with one or the other of said chutes, and means actuated by the movable member of the main conveyer for driving the endless belt of the attachment.

6. A portable attachment for a main conveyer having a continuously movable member, comprising a frame, a pair of chutes 115 extending in different directions, an endless belt for guiding packages on to the main conveyer adapted to be adjusted to cooperate with one or the other of said chutes, and driving means adapted to cooperate with and be 120 directly driven by the main conveyer for actuating the belt of the attachment.

7. A portable attachment for a main conveyer having flights arranged at intervals thereon, comprising a frame, a pair of chutes 125 thereon extending in different directions, an endless belt conveyer adjustably mounted on the frame and adapted to cooperate

with one or the other of said chutes, and a driving mechanism for the endless belt of the attachment comprising a driving chain having lugs adapted to cooperate with 5 and be actuated by the flights of the main conveyer.

8. A portable attachment for a main conveyer having lugs arranged at intervals thereon, comprising a frame, an auxiliary 10 conveyer mounted thereon and arranged to transmit articles from a high level to the main conveyer at a lower level, lugs positioned at intervals on the auxiliary conveyer against which the articles rest so that they 15 are delivered to the main conveyer at predetermined intervals, and means actuated by the lugs on the main conveyer for operating the auxiliary conveyer.

9. A portable attachment for a main conveyer having lugs arranged at intervals 20 thereon, comprising a frame, an auxiliary conveyer mounted thereon and arranged to transmit objects from a high level to the main conveyer at a lower level, a plurality 25 of gravity chutes mounted at the top of said frame and adapted to deliver articles to the auxiliary conveyer, means for adjusting said auxiliary conveyer to place it in operative connection severally with said gravity 30 chutes, and means actuated by the lugs of the main conveyer for operating the auxiliary conveyer.

10. A portable attachment for a main conveyer having lugs arranged at intervals 35 thereon, comprising a frame, an auxiliary conveyer mounted thereon and arranged to deliver objects from a high level to the conveyer at a lower level, means for adjusting 40 said auxiliary conveyer in a lateral direction, and means actuated by said lugs for operating the auxiliary conveyer.

11. An attachment for conveyers having a movable member with flights thereon, comprising means for feeding objects to the conveyer, and means adapted to be actuated by 45 said flights for operating said feeding means.

12. A conveyer attachment comprising a frame, a plurality of fixed gravity chutes mounted thereon, an inclined chute movably 50 mounted on said frame, and means for actuating said chute to produce a lateral movement thereof to co-operate with one of said gravity chutes.

13. A conveyer attachment comprising a 55 frame, laterally disposed spaced adjusting screws, an inclined chute mounted thereon, and means for operating said screws to produce a lateral movement of said chute.

14. A conveyer attachment comprising a 60 frame, a laterally movable chute mounted thereon, spaced adjusting screws in engagement with said movable chute, a sprocket wheel disposed on each of the adjusting screws, an endless chain interconnecting said 65 sprocket wheels, and a crank attachable to

one of the adjusting screws for effecting the operation thereof to produce lateral movement of the chute.

15. A portable destacker comprising a frame, a pair of oppositely extending inclined gravity chutes projecting from the upper portion of the frame, a laterally movable inclined chute operatively mounted on the frame and adapted for adjustment so that its higher end registers with the lower end 70 of one of the gravity chutes, and means for adjusting the laterally movable chute.

16. The combination with a main conveyer moving in a predetermined direction, of a portable conveyer attachment, comprising a frame, a travelling belt carried thereby, and interconnecting mechanism cooperating with the main conveyer for driving the working portion of the travelling belt in a direction substantially the same as that of the main 80 conveyer.

17. The combination with a main conveyer provided with flights moving in a predetermined direction, of a portable conveyer attachment adapted to be positioned above the 90 conveyer, comprising a frame, a travelling belt carried thereby, a driving chain provided with flights disposed above and in cooperative driving engagement with the flights of the main conveyer, and means interposed between the driving chain and the belt for driving the carrying portion of said travelling belt in a direction substantially 95 the same as that of the main conveyer.

18. The combination with a main conveyer 100 having a series of flights, of a portable conveyer attachment adapted to be positioned above the main conveyer and comprising a frame, a travelling belt carried by the frame, a driving chain provided with flights and having a stretch of the chain normally disposed in a plane parallel to the main conveyer, driving means for interconnecting the chain and the travelling belt, a plurality of 105 wheels supporting the frame, and means for taking the weight of the attachment from certain of the wheels to render the portable attachment immovable and for subsequently lowering one end of the attachment to bring the flights of the driving chain into 110 driving engagement with those of the main conveyer.

19. In combination with a main conveyer, a portable attachment comprising a frame, a laterally movable inclined chute mounted 115 thereon, an inclined travelling belt associated therewith, means cooperating with the main conveyer for operating the inclined belt, a plurality of wheels normally supporting the frame, and means adapted to rest 120 on the floor and take the weight from certain of the wheels and render the attachment immovable under operating conditions.

20. The combination with a main conveyer 125 provided with flights, of a portable conveyer 130

attachment adapted to be disposed above the main conveyer and comprising a frame, a travelling belt supported on the frame, a driving chain carried by the frame adapted to be raised and lowered relative thereto and provided with flights, interconnecting operating mechanism between the driving chain and the travelling belt, and means for lower-

ing and raising the driving chain into and out of operative driving engagement with the main conveyer.

In witness whereof we have hereunto set our hands this 18th day of November, 1919.

GRADY E. FAIRCLOTH.
WILLIAM M. MOSELEY.
